(No Model.)

D. BROWN.

CARTRIDGE RELOADING IMPLEMENT.

No. 329,135.

Patented Oct. 27, 1885.

WITNESSES.

INVENTOR

Daniel Brown

UNITED STATES PATENT OFFICE.

DANIEL BROWN, OF JOHNSTON, RHODE ISLAND.

CARTRIDGE-RELOADING IMPLEMENT.

SPECIFICATION forming part of Letters Patent No. 329,135, dated October 27, 1885.

Application filed July 10, 1885. Serial No. 171,248. (No model.)

To all whom it may concern:

Be it known that I, DANIEL BROWN, of Johnston, in the county of Providence, in the State of Rhode Island, have invented a certain new and useful Improvement in Tools for Loading and Reloading Cartridge-Shells; and I declare the following to be a specification thereof, reference being had to the accompanying drawings.

10 Like letters indicate like parts.

Figure 1 is a side elevation of my invention. Fig. 2 shows, partly in side elevation and partly in vertical section, the tool as used in removing an exploded primer. Fig. 3 is a side elevation of the tool, showing its use in seating the primer. Fig. 4 shows, partly in side elevation and partly in vertical section, the tool as used in seating the bullet in the shell. Fig. 5 is a side elevation of my invention, illustrating the operation of the tool in expelling the cartridge when loaded. Fig. 6 is the front end elevation of the tool.

My invention is adapted for the loading and reloading of the metallic shells of pistol and rifle cartridges; and it consists of a combination of several working parts, as hereinafter particularly described, and specifically mentioned in the claims, whereby the operations of capping, uncapping, and loading cartridge-shells are performed by a single implement, instead of by separate tools for each purpose, as heretofore common.

Construction: A handle, A, is bifurcated, as shown at *a a* in Fig. 6. It has a vertical groove, *b*, a transverse slot, *c*, and two sloping seats, *d e*, which are best shown in Figs. 2 and 6. A supporting-block, B, has the following appendages: a stud, C, a tube or sleeve, D, and two prongs or jaws, E. The handle A is pivoted 40 to the block B by the pin *f*. A handle or lever, F, whose upper end is bent at a right angle, is mounted upon the pin *f*, which pin, passing through the handles A F and block B, holds said parts together. The shorter arm, G, 45 of the lever F is reduced in width about one-half, as is most plainly shown in Fig. 2, and is provided with a set-screw, *g*. The stud C is made of a sufficient diameter to fit the interior of the cartridge-shell, and near its junction with the supporting-block B its diameter enlarges upwardly, as shown in the several figures, to give it the form of a truncated cone.

The stud C has a central bore through which extends the expelling-pin *h*. As shown in Fig. 2, the pin *h* is reduced in diameter at its lower end, and at its upper end has a knob or head which prevents it from falling out. The tube or sleeve D at its lower end has the inwardly-projecting or annular beveled lip *i*. (Seen in Fig. 2.) A movable chamber, H, 60 whose lower edge is beveled, as shown in Fig. 2, is mounted upon the lever F by the pivot *j*, and has a longitudinal sliding movement within and along the sleeve D, which movement is imparted to it by the action of the lever F. The interior of the chamber H is best shown in Fig. 4, by which it is seen that its bore is conical at top. The lever F is slotted in the inclined and peculiar form shown in Figs. 2 and 4 for the reception of the pin *j*. 70 Shoulders *m* are made on the inner surfaces of the bifurcations *a* of the handle A, and these serve as stops to limit in either direction the inward swinging of the block B. These shoulders are shown in front elevation in Fig. 6, 75 and by dotted lines in Figs. 1 and 3.

Operation: The operation of removing an exploded primer is illustrated in Fig. 2. The cartridge-shell is slipped upon the stud C, while the tool is in the position shown in Fig. 80 1. By raising the lever F the supporting-block B is swung inwardly to the position shown in Fig. 2, which brings the base of the cartridge-shell upon the seat *d*. By still further raising the lever F its short arm G presses 85 down the expelling-pin *h*, the lower or smaller end of which passes through the central vent of the anvil of the shell and forces out the exploded primer from the pocket. The cap thus expelled falls out through the groove *b*, as 90 shown in Fig. 2. The angular slope of the seat *d* gives a wedge-like action to drive the shell farther up on the stud C as it swings inwardly, and this movement expands the mouth or rim of the shell, if bent, and restores it to a 95 true circular shape to receive the ball again.

To insert a new primer, I enter it with the fingers in the pocket of the shell and then place the shell in the position shown in Fig. 3. The jaws E of the block B thus embrace the shell 100 above its flange, while the arm G bears up against the shell beneath. By bringing the handles A F together the cap is forced into the pocket of the shell. The set-screw *g* presses

against the cap to seat it in place, and being adjustable can be regulated to force in the cap to the desired depth. As cartridge-shells of different makes vary in the depth of the 5 primer-pocket, it is important to have the cap-seating surface adjustable. I for that reason use a set-screw.

To seat the bullet in the shell, I enter the bullet in the mouth of the shell with the fingers 10 before placing the cartridge in the loading-chamber, and insert the cartridge through the open end of the tube D up into the bore of the chamber H, when the tool is in the position shown in Fig. 2. I then swing the support- 15 ing-block B inwardly, and thereby bring the flanged end of the shell upon the seat e of the handle A, as seen in Fig. 4. By pressing upon the lever F the chamber H descends into the tube D as far as the lip i, and surrounds 20 and slides over and along the shell until the conical part of the bore engages with the ball and then forces it into the shell.

In order to obtain the great pressure requisite for properly seating the ball in the shell, 25 I make a slot in the lever F of the shape shown at k in Figs. 2 and 4. By having the bearing at the top of the slot on an incline the friction of the chamber H on the tube D is lessened at the point where the greatest strain is re- 30 quired—namely, at the latter part of its motion as it descends—and by the inclination of the slot the leverage is also increased at the same point. A round or horizontal slot would cramp the chamber H when at that point, and would 35 not counteract the friction caused by the tendency of the chamber toward the pivot, and would not allow the proportionally longer sweep of the lever F, which the inclined slot permits. The reason of such increase of le- 40 verage is because the chamber H travels relatively a less distance in proportion to the sweep of the lever F, and consequently gains power.

To expel the loaded cartridge from the 45 chamber H, the lever F is raised, which withdraws the chamber within the tube D. The annular lip i bearing against the flange of the shell holds it in position while the chamber is withdrawn from it. The power is thus ap- 50 plied directly in a straight line, and the lip i fitting loosely allows the cartridge to drop out, as shown in Fig. 5.

I claim as a novel and useful invention, and desire to secure by Letters Patent—

55 1. In a cartridge implement, the combination of the bifurcated handle A, having the inclined seat d, the lever F, the swinging supporting-block B, pivoted to said handle and lever, and the stud C, conically enlarged in 60 diameter at its upper portion for the purpose of properly shaping the open end of a cartridge-shell, substantially as specified.

2. In a cap-seating cartridge-tool, the combination of the block B, having jaws E, and the lever F, pivoted to said block, and having 65 its arm G provided with a set-screw adjustable in said arm, substantially as and for the purpose specified.

3. The combination of the bifurcated handle A, having the seat e, the block B, pivoted at 70 f to said handle A, and having the tube D, the lever F, pivoted at f to said handle A, and the chamber H, mounted upon the lever F by the pivot j, and movable longitudinally in the tube D, for the purpose of seating the bullet in the 75 cartridge-shell, substantially as shown.

4. The combination of the bifurcated handle A, having the seat e, the block B, pivoted at f to said handle A, and having the tube D, the lever F, pivoted at f to the handle A, and 80 having the slot k, and the chamber H, movable longitudinally within the tube D, and mounted upon the pin j in the lever F through said slot k, whereby the power of the lever F is increased during the operation of seating the 85 bullet in the cartridge-shell, substantially as described.

5. In a cartridge implement, the cartridge-shell-extracting device, consisting of the combination of the bifurcated handle A, the block 90 B, pivoted at f to said handle A, the tube D, having the annular beveled lip i, the lever F, pivoted at f to said handle A and block B, and the chamber H, mounted upon the lever F by the pivot j, and movable longitudinally 95 in said tube D, and having its lower end beveled externally, substantially as specified.

6. The combined cartridge capping, uncapping, and loading implement herein described, 100 consisting of the bifurcated and grooved handle A, having the inclined seats d e, the block B, pivoted to the handle A at f, and having the jaws E, the centrally-bored stud C, through which extends the expelling pin h, the lipped tube D, the lever F, pivoted at f to said handle A and block B, and having a cap-seating arm, G, and the chamber H, mounted on said lever F by the pin j, substantially as specified. 105

7. The combination of the bifurcated and grooved handle A, having the angular seat d, the swinging block B, pivoted at f to the handle A, having the centrally-bored stud C, through which extends longitudinally the expelling-pin h, the lever F, pivoted to the handle A and block B at f, and having an 110 arm, G, to swing the block B inwardly, so as to bring a cartridge-shell upon the seat d, and also to operate the expelling-pin h, substantially as described.

DANIEL BROWN.
